UNITED STATES PATENT OFFICE.

LADISLAS LUKI, OF COLUMBUS, OHIO.

PARACHUTE.

1,104,995.

Specification of Letters Patent. Patented July 28, 1914.

Application filed May 16, 1914. Serial No. 839,022.

To all whom it may concern:

Be it known that I, LADISLAS LUKI, a subject of the King of Hungary, residing at Columbus, in the county of Franklin and State 5 of Ohio, have invented certain new and useful Improvements in Parachutes, of which the following is a specification.

An object of the invention is to provide a parachute that is so controlled from a carriage as to determine the velocity of descent of the same.

A further object of the invention is to provide a parachute with ribs, stretchers, and a runner, with ropes connected to the 15 edge of the parachute cover and terminating in a single cable to be wound upon a windlass disposed within the parachute carriage, so that the cover may be opened or closed the desired distance to control the velocity 20 of descent of the parachute.

With the above and other objects in view that will appear as the nature of the invention is better understood, the same consists in the novel construction, combination and 25 arrangement of parts to be hereinafter more fully described and then claimed.

In the accompanying drawing in which is shown a preferred embodiment of my invention and to which reference is had here- 30 in by like characters designating correspond- ing parts throughout the several views:— Figure 1 is a vertical sectional view of the parachute distended. Fig. 2 is a vertical sectional view of a portion of the device 35 with the cover removed. Fig. 3 is a horizontal sectional view of the same taken on line III—III of Fig. 1, and, Fig. 4 is a detail sectional view of a portion of the carriage frame for reducing friction on the 40 ropes.

Referring more in detail to the accom- 45 panying drawing, the reference numeral 10 designates the tubular rod which constitutes the central shaft of the parachute and is exteriorly threaded at its upper end for the reception of the head cap 11. The head cap 11 is suitably recessed in its sides for the reception of the upper ends of the ribs 12, the ribs 12 being pivoted thereto as at 50 13 while the lower ends of the said ribs are provided with eyes 14. Mounted on the tubular rod 10 is a runner 15 and extending between the runner 15 and the ribs 12 are the stretcher arms 16. A cover of canvas 55 or other suitable material as 17 is provided and is connected to the ribs 12 and head cap

11 in the usual manner and is of a size in distended position to prevent the runner 15 descending to a point which would place the stretcher arms 16 in horizontal position. 60

A carriage is suspended from the tubular member 10 and consists of the side arms 18 inclined upwardly and inwardly and fixed to the lower end of the tubular member 10 as at 19, while the lower ends thereof support the bottom 20 of the carriage, and side rails 21 extend about the lower ends of the side arms 18. A windlass 22 is mounted upon the bottom 20 of the carriage and has wound thereon a cable 23, the cable 23 being the continuation of a plurality of ropes 24 extending between the eyes 14 of the ribs 12 and the point 25 of the said cable. Means are provided to reduce the friction and wear on the ropes 24 and consist of the rollers 26 suitably supported in the frame 27 connected to the side arms 18, the ropes 24 passing over the rollers to the point 25, the said rollers 26 being mounted on the shafts 28. 80

In collapsed form the parachute resem- 85 bles the ordinary type. When the same is distended as shown in Fig. 1, the velocity of the descent is controlled by a person within the carriage. By operating the windlass 22 to wind thereon the cable 23, the ropes 24 are moved inwardly the desired distance to reduce in size the parachute covering 17, thereby reducing the resisting surface of the cover and permitting the para- 90 chute to descend more rapidly. In order to provide for a gradual descent, the cable 23 is unwound from the windlass 22 which will permit the ribs 12 to be distended, thereby increasing the resistance surface of the cover 17. By operating the windlass, the parachute may be entirely closed and in view of the particular size of the covering 17 as before mentioned, the runner 15 is prevented from descending to a point where it would be impossible to collapse the same. 100

While I have herein shown and described the preferred embodiment of my invention, I do not wish to confine myself to the exact details of construction as shown, as various forms, modifications and arrangement of the parts may be had without departing from the spirit and scope of the invention as claimed. 105

What I claim as new is:—

1. In a parachute, a central tubular rod, ribs pivoted at their upper ends to said rod,

- a runner mounted on the rod, stretchers extending between the runner and the ribs, a canvas covering for said ribs, a carriage suspended from the lower end of the rod,
5 ropes connected to the lower ends of the ribs and terminating in a single cable that extends into the carriage, and a windlass within said carriage on which the cable is wound.
- 10 2. In a parachute, a central rod, ribs pivoted at their upper ends to said rod, a runner mounted on the rod, stretchers extending between the runner and the ribs, a covering for the ribs, side arms connected to the lower end of the rod, a carriage carried by said side arms, ropes connected to the

free ends of the ribs and terminating in a single cable extending into the carriage, means within the carriage on which the cable is wound and unwound for controlling the opening and closing of the ribs and cover, a frame carried by the side arms, and rollers carried by said frame over which said ropes operate in winding and unwinding the cable. 20

In testimony whereof I affix my signature in presence of two witnesses. 25

LADISLAS LUKI.
